[57] ABSTRACT

A wrist-watch casing comprises a casing body, a bezel, a blind bore formed in either of the casing body or the bezel, and a metal coil tightly wound and plated with fusing alloy. The metal coil is inserted into said bore and fusingly attached to the inner wall of the bore, and a threaded member screwed to the metal coil which forms the female thread, so that a casing back or the bezel can be rigidly connected to the casing body.

FIG. 1 FIG. 2**FIG. 3****FIG. 4****FIG. 5**

FIG. 6**FIG. 7****FIG. 8**

WRIST-WATCH CASING

The present invention relates to a wrist-watch casing assembled by means of screws which connect a casing back to a central casing body or a bezel to a casing body.

Recently, it has been attempted to improve the character of a wrist watch casing under any conditions, which may cause rust and corrosion of the internal mechanism of the watch, but these attempts have not been successful with new materials giving various designs to the wrist watch casing.

Thus, the prior art screw threaded connection could not be adopted in a wrist-watch casing assembly made of such materials as stainless steel, cemented carbides and ceramics, because a threaded bore for screw insertion could not be formed in such material without its destruction.

Of course, in order to allow the parts of the wrist-watch casing to be detachable, and adhesive could not be used.

An object of this invention is to provide a wrist watch casing which can have a threaded bore in a bezel or casing body, even if it is made of a material such as stainless steel, cemented carbide and ceramics, characterized by hard machinability.

This and other feature and advantages of this invention will be understood from the following description with reference to the accompanying drawing, in which:

FIG. 1 is a cross-sectional view of a blind bore and a metal coil to be inserted into said bore, according to an embodiment of this invention;

FIG. 2 is a cross-sectional view of a threaded bore formed by means of this invention, and a screw cooperating with this bore;

FIG. 3 is a cross sectional view of a screw threaded connection according to this invention;

FIG. 4 is a front view of a wrist-watch casing embodying the present invention;

FIG. 5 is a cross section of the watch casing taken along the line A—A of FIG. 4.

FIG. 6 is a cross section similar to FIG. 5 of another embodiment of this invention in which the watch casing is sectioned along a line similar to line A—A in FIG. 4;

FIG. 7 is a cross section similar to FIG. 5 of a further embodiment of this invention in which the watch casing is sectioned along a line similar to line A—A in FIG. 4; and

FIG. 8 is a cross section similar to FIG. 5 of still another embodiment of this invention in which the watch casing is sectioned along a line similar to line A—A in FIG. 4.

Referring to the drawings, a blind bore 1 is formed in a bezel 2 (shown in FIGS. 4 and 5) or a casing body 3 (shown in FIGS. 6 and 7). The bezel 2 or casing body 3 is made of stainless steel and the bore 1 has a circular inner wall to be smooth. A metal coil 4, for example, a stainless steel coil tightly wound (i.e. with successive turns in axial contact) is coated or plated with fusing alloy, for example, nickel phosphide. The plated layer may have a thickness of approximately 10 microns. Said plated coil 4 is tightly inserted into said bore 1 and heated at a temperature of about 1,100°C in a non-oxidizing furnace so that the alloy is fused in the bore 1 thereby to bond the coil, as a threaded portion, in the bore 1. The diameter of the coil 4 may be slightly less

than that of the bore 1 in order to avoid the deformation of the thread and incomplete brazing.

Into the threaded bore 1 may be detachably inserted a screw 5 which has a helical threaded portion with an arc rate cross-section (shown in FIGS. 2 and 3). The threaded portion may be provided with a rhombic cross-section. In an embodiment of FIGS. 4 and 5, the wrist watch casing has a bezel 2 with threaded bores 1 and a one-piece type casing body 3 having through-going bores 6 through which screws 5 are threaded to the bores 1 so that the bezel 2 is tightly connected to the casing body 3 to maintain a waterproof seal. A glass plate 7 is rigidly supported through a packing ring 8 to the front surface of the casing body 3 by pressure from the bezel 2 along all of the edges of the glass plate 7. In another embodiment of FIG. 6, the wrist-watch casing is separated to two pieces, a center casing body 9 and an inner body 12.

The threaded bores 1 are formed in the center casing body 9, into which are inserted screws 5 each passing through a bore 11 formed at the peripheral portion of a casing back 10.

Accordingly, the inner body 12 is supported tightly to a bezel portion integrally formed with the center casing body 9 by the compression by casing back 10 of the body 12 via a packing ring 13.

In still another embodiment shown in FIG. 7, a casing back 10 is integrally formed with an inner body 12 and separates from an attaching ring 14. Thus attaching ring 14 has through bores 15 through-going which screws 5 are passed to be threaded into threaded bores 6 formed in a center casing body 9, so that the casing back 10 is fixed to the center casing body 9 together with a glass plate 7 and a packing ring 8.

FIG. 8 depicts an embodiment of the wrist-watch casing of a screw-back type. In this embodiment, a casing back 10 is threaded to a large threaded bore 6 formed in the back portion of a center casing body 9. A screw 5 is integrally formed with the casing back 10, and the threaded bore 6 is produced by the coil device mentioned above.

The blind bore 1 may be coated with nickel before the insertion of the coil 4 in the case in which the blind bore 1 is formed by means of erosion, electro-beam, supersonic vibration, laser beam, etc., in a bezel or casing body of such material as cemented carbide and ceramics, whereby the coil 4 is tightly attached to the peripherally of the bore 6 because the nickel coating has excellent affinity for the brazing. Silver is preferably utilized as a coating material.

What is claimed is:

1. A wrist-watch casing comprising:
a casing member, a bezel member and a back member interconnected to define a watch-casing structure;

a blind bore formed in one of said members;
a helical metal coil of mutually adjoining turns of circular cross-section received in said bore and fused to the wall thereof to form a female thread; and
a male threaded element threaded into and removable from said female thread to retain another of said members against said one of said members.

2. The casing defined in claim 1 wherein said one of said members is made of stainless steel and said coil is composed of stainless steel coated with nickel phosphide fused to the wall of said bore.

3. The casing defined in claim 1 wherein said one of said members is composed of a material selected from the group which consists of cemented carbide or ceramic, said wall of said bore having a nickel coating fused to said coil.

4. The casing defined in claim 1 wherein a throughgoing bore is formed in said other member and said element is a screw traversing said throughgoing bore.

5. The casing defined in claim 1 wherein said element is a threaded projection formed unitarily on said other member.

6. The casing defined in claim 1 wherein said bore is formed in said bezel member, said casing member being provided with a throughgoing bore registering with said blind bore, said element being a screw tra-

versing said throughgoing bore, said bezel member clamping a glass plate and a sealing ring against said casing upon tightening of said screw.

7. The casing defined in claim 1 wherein said blind bore is formed in said bezel, said back member having a throughgoing bore along with said blind bore, said element being a screw traversing said throughgoing bore and clamping said bezel member against said casing member and said back member, said casing further comprising a sealing ring interposed between at least two of said members.

8. The casing defined in claim 7 wherein said pack member is a ring surrounding said casing member.
